(57) **CLAIM**

The ornamental design for a display panel with animated graphical user interface displaying alcoholic fermentation, as shown and described.

DESCRIPTION

FIG. 1 is a front view of a first image in a sequence of a display panel with animated graphical user interface displaying alcoholic fermentation showing our new design; FIG. 2 is a second image thereof; FIG. 3 is a third image thereof; FIG. 4 is a fourth image thereof; FIG. 5 is a fifth image thereof; FIG. 6 is a sixth image thereof; FIG. 7 is a seventh image thereof; FIG. 8 is an eighth image thereof; FIG. 9 is a ninth image thereof; and, FIG. 10 is a tenth image thereof.

The broken lines in the drawings show portions of an animated graphical user interface that form no part of the claimed design. The appearance of the animated images sequentially transitions between the images shown in FIGS. 1-10. The process or period in which one image transitions to another forms no part of the claimed design.
